UNITED STATES PATENT OFFICE.

HENRY BRAUMOELLER AND HERMAN MUELLER, OF CHICAGO, ILLINOIS.

SHOW-CASE STAND.

SPECIFICATION forming part of Letters Patent No. 248,283, dated October 18, 1881.

Application filed April 18, 1881. (No model.)

To all whom it may concern:

Be it known that we, HENRY BRAUMOELLER and HERMAN MUELLER, of Chicago, in the county of Cook and State of Illinois, have 5 invented a certain new and useful Improvement in Show-Case Stands, of which the following is a specification.

The object we have in view is to produce a suitably braced and connected stand for supporting show-cases which can be readily adjusted in height without changing or removing any of the parts; and our invention consists in the peculiar devices employed by us for this purpose, as fully hereinafter explained, 15 and pointed out by the claim.

In the accompanying drawings, forming a part hereof, Figure 1 is a side elevation of the stand; Fig. 2, an end view of the same; Fig. 3, a horizontal section of one end of the stand 20 on line 3 3, and Fig. 4 a horizontal section of one end on line 4 4.

Like letters denote corresponding parts in all four figures.

The stand has two standards, one at each 25 end thereof. Each standard is constructed in two parts, A B, having any suitable ornamental design. The lower part, A, is extended laterally to form feet, while the upper part, B, is also extended laterally on each side of a central line to form brackets for supporting a show-case. The part A of each standard is cast 30 with ways a on its inner side, between which ways slides the lower end of the part B, such part B having a central vertical slot, b. The 35 parts B of the two standards are connected by a central horizontal bar, C, which is secured rigidly to the upper edges of such parts.

Braces D D' are secured to the central bar, C, and extend outwardly and downwardly to the inner sides of the parts B of the standards, 40 near their lower ends. The lower ends, c, of the braces D D' are bent into vertical positions, as shown, and are provided with long vertical slots d, which coincide with the slots b, and are made long enough to permit of any 45 ordinary or desirable adjustment.

The parts A of the two standards are connected by a horizontal rod, E, the ends of which pass through the slots d of the braces and the slots b of the parts B, and also through 50 holes in the parts A, near the tops of the same.

The rod E has shoulders or collars e near its ends, between which and the nuts f on the screw-threaded ends of the rod the parts of the standards and the braces are rigidly clamped. 55

By loosening the nuts f it will be seen the height of the stand can be changed as desired. The stand at the same time is exceedingly stiff and strong, the standards having double horizontal connections and lateral braces. 60

What we claim as our invention is—

In a show-case stand, the combination, with the standards composed of parts A B, sliding together, the parts B, having slots b, of the bar C, braces D D', having slotted lower ends, and 65 the rod E, provided with collars e and nuts f, all constructed and arranged substantially as described and shown.

HENRY BRAUMOELLER.
HERMAN MUELLER.
